United States Patent Office

Des. 180,224
Patented May 7, 1957

180,224

DESK

Victor E. Delynn, Mount Vernon, N. Y.

Application March 30, 1956, Serial No. 40,840

Term of patent 7 years

(Cl. D33—7)

FIG. 1.

FIG. 2.

FIG. 3.

FIG. 4.

Fig. 1 is a front perspective view of a desk, showing my new design;

Fig. 2 is a rear elevational view thereof;

Fig. 3 is a side elevational view; and

Fig. 4 is a bottom plan view.

The dotted lines are for illustrative purposes only.

I claim:

The ornamental design for a desk, substantially as shown and described.
